UNITED STATES PATENT OFFICE.

HANNIBAL C. FORD, OF NEW YORK, N. Y., ASSIGNOR TO FORD INSTRUMENT COMPANY, INC., A CORPORATION OF NEW YORK.

SIGNAL SYSTEM.

1,420,030.

Specification of Letters Patent. Patented June 20, 1922.

Application filed October 10, 1917. Serial No. 195,692.

To all whom it may concern:

Be it known that I, HANNIBAL C. FORD, a citizen of the United States, residing at the city of New York, in the borough of 5 Queens and State of New York, have invented certain new and useful Improvements in Signal Systems, of which the following is a full, clear, and exact description.

This invention relates to signal systems 10 and more particularly to systems by means of which intelligences are electrically transmitted from a central to one or more substations. The invention has a particular adaptation to a signal system consisting of a 15 transmitter and a receiver which are connected together by a plurality of circuits which are successively closed at the transmitter to energize different poles of a multipole receiver at the substation and cause 20 them to act upon a rotary armature to effect successive changes in its angular position.

One of the objects of the invention is to provide an improved form of transmitter for a signal system of this type, which transmitter is so constructed that it is adapted 25 to be continuously operated and yet the switches which control the circuits to the poles of the receiver are intermittent and quick acting in operation, to thereby prevent 30 erroneous readings being obtained at the receiver when a plurality of receivers are combined together to give a single reading.

Another object of the invention is to provide a transmitter in which the parts are 35 compactly arranged and the counter-wheels and switch operating mechanisms are directly connected together.

A further object of the invention is to provide a transmitter having the switches 40 and mechanism for operating the same of a simple construction and positive in their operation.

A still further object of the invention is to provide a receiver of the multipole type, in 45 which the rotary armature can be moved successively to a plurality of intermediate positions between each pair of poles.

The invention also has for its object the provision of a receiver in which the pole 50 pieces and the polarized rotary armature are both magnetically energized in such a manner that the attraction between parts of unlike polarity and the repulsion between parts of like polarity are utilized to cause 55 the angular displacement of the armature.

With these and other objects in view the invention consists of the constructions and combinations which will be hereinafter described in detail in connection with the accompanying drawings, and will be particularly pointed out in the appended claims.

One embodiment of the invention is shown, which embodiment is especially adapted for transmitting ranges to one or more receiving stations, as for example, 60 from a range finder to a plurality of gunners' stations.

In the drawings,—

Figure 1 shows the transmitter, the casing of the same being partially broken away. 70

Figure 2 is a receiving instrument, which is adapted to be connected to the transmitter by a plurality of circuits, the casing of this instrument also being partially removed 75 in order to more clearly show the parts.

Figure 3 is a central vertical section through the transmitter.

Figure 4 is an end view of the transmitter.

Figure 5 is a section of the transmitter 80 on the line 5—5 of Figure 3.

Figure 6 is a section of a slightly modified construction.

Figure 6^a is an end view of Figure 6.

Figure 7 is a section on the line 7—7 of 85 Figure 3.

Figure 8 is a section on the line 8—8 of Figure 3.

Figure 9 is a section on the line 9—9 of Figure 3.

Figure 10 is a transverse detail partially 90 in section along the line 10—10 of Fig. 1, showing the lost motion connection between the operating shaft and the cam shaft which actuates the switches.

Figure 11 is a central longitudinal section 95 of the construction shown in Figure 10.

Figure 12 is a central longitudinal section of one of the multipole receivers taken along the line 12—12 of Fig. 13.

Figure 13 is a transverse section on the 100 line 13—13 of Figure 12, showing one position of the rotary armature.

Figures 14, 15 and 16 are views similar to Figure 13, showing the other positions which the rotary armature successively assumes 105 when passing from one pole piece to another; and

Figure 17 is a diagrammatic view of the electrical connections.

Referring first to Figures 1 and 2, the 110

transmitter and receiving instrument which are shown in these views are adapted to transmit ranges from five thousand to twenty-five thousand yards. For this purpose the transmitter is provided with two counter-wheels and the receiving instrument with two receivers. The two counter-wheels of the transmitter are connected together by intermittent gearing so that one complete 5 turn of one wheel will cause a small angular displacement of the other while the two receivers are independent of each other, but are connected to the switches of the transmitter by a series of electrical circuits, as 10 15 will be hereinafter described.

The two counter-wheels of the transmitter are designated 1 and 2, which wheels have, for the specific embodiment of the invention illustrated, different numerals thereupon, the wheel 2 carrying the numbers 00, 20 05, 10, 15, etc., up to 95, and the wheel 1 carrying the numbers 5 to 24, inclusive. As ranges are usually indicated only to within 50 yards, a separate fixed cipher "3" is utilized, which is the digit column, the counter-wheel 2 being the 10's and 100's column and the counter-wheel 1 being the thousandths and ten thousandths columns. The numbering upon the counter-wheels is duplicated 25 30 35 upon the dials 5 and 6 of the receiver, which dials correspond to the counter-wheels 1 and 2, respectively, a fixed cipher, which is indicated at 7, being also utilized in the receiver for the same purpose as in the transmitter.

Referring now to the construction of the transmitter, any suitable casing 8 may be provided for it, in which it is housed. The transmitter comprises a base plate 9 having end standards 10 and 11 and intermediate standards 12 and 13 secured thereto. Mounted between the standards 11 and 13 is a shaft 14 and similarly mounted between the standards 10 and 12 is an axially aligned shaft 15, the counter-wheels 1 and 2 being 40 45 respectively fastened to the inner ends of these shafts so that these counter-wheels are in abutting relation, the numbers upon these counter-wheels appearing below an elongated opening in a plate 16, which is secured 50 to the top of the standards 12 and 13.

Secured upon the top face of the base plate 9 and insulated therefrom, are a plurality of transversely extending bars which are indicated 17, 18, 19, 20, 21, 22, 23, 24, 25 and 26. 55 Each of these bars carries two pairs of pivoted arms 27 and 27', which arms at their upper ends carry electrical contacts 28 and 29 each of which serve to connect the upper ends of a pair of arms together. These movable contacts are adapted to engage with and close the circuit through stationary contacts, which are mounted upon bus bars. Four of these bus bars are shown in the specific embodiment illustrated, and are indicated 30, 31, 32 and 33. Each of these

bus bars carries stationary adjustable contacts, and as is shown in Fig. 4 of the drawing, each contact comprises a terminal 34 and a threaded end 35 having a slotted head so that the contact may be turned in the bus 70 bar to adjust its position relative to the movable contact with which it engages. Two sets of five pairs each of movable contacts are shown so that in all there are twenty pairs of fixed and movable contacts through 75 which twenty different circuits may be closed to the receiver, as will be hereinafter described in connection with the diagram of the electrical circuits and the operation of the system. 80

The movements of the movable contacts are controlled by cam shafts 36 and 37, which are sleeves mounted upon the shafts 14 and 15, respectively, each cam shaft consisting of a cylinder of fiber or other suitable material having segmental cut-outs opposite each pair of pivoted contacts, which cut-outs are disposed in different angular positions for each respective pair of contacts. Each segmental slot is of a depth to permit a movable contact to move inwardly to close a circuit through its fixed contact when the slot comes opposite the arm carrying the contact. This inward movement of the contacts is obtained by providing a spring 38 between each pair of pivoted contacts. In order to eliminate the friction between the pivoted arms and the cam shafts rollers 39 may also be provided, which rollers engage with the surface of the cam instead of having the arms engage directly with the cam shafts. 90 95 100

The shafts 14 and 15 carrying the counter-wheels 2 and 1 and the cam shafts 36 and 37, respectively, are connected by intermittent gearing so that a complete rotation of the counter-wheel 2 will cause the angular advance of the counter-wheel 1 through one-tenth of a revolution. This gearing will now be described. 105 110 115

A shaft 40 is rotatably mounted between the standards 12 and 13 beneath the two counter-wheels. The shaft 40 carries a pinion 41 at the righthand end thereof, as shown in Fig. 3, which pinion has its alternate teeth extending entirely across and half way across the pinion, respectively, so that the right hand half of this pinion or 41^a has a full number of teeth and the left hand half of the pinion, 41^b, has only half a full number of teeth (see Fig. 3). The right hand half 41^a of the pinion 41 engages a mutilated gear 42 and the left hand half 41^b a mutilated gear 43. The mutilated gear 42 is provided with two full teeth, which are shown clearly in Fig. 5, and are numbered 44 and 45, the remainder of this gear being cut away to the root circle, as at 46. The other mutilated gear 43 comprises a cylindrical surface which is provided with a recess 48 120 125 130

whose sides coincide with the inner adjacent sides of the two teeth 44 and 45 upon the gear 42. The relation between the recess and the teeth may also be seen from Fig. 10 which shows a similar structure as will hereinafter appear. Two of the teeth of pinion 41^a normally rest upon the surface of mutilated gear 43 and prevent the pinion 41 from turning inadvertently. The shaft 40 carries at its other end a pinion 50 which meshes with a gear 51 carried by the counter-wheel 1. When the counter-wheel 2 makes a complete revolution the gear teeth 44 and 45 will be brought into mesh with the pinion 41^a and the tooth of pinion 41^b will ride in the recess 48, which will cause a partial rotation of the shaft 40 and the counter-wheel 1. The pitch and diameter of the pinions and gears are so proportioned that one complete revolution of the counter-wheel 2 causes a tenth of a revolution of the counter-wheel 1.

The shaft 14 which carries the counter-wheel 2 is adapted to be rotated through the lost motion connection shown specifically in Figs. 10 and 11 for the purpose of imparting a quick intermittent action to the cam shaft 36 for a continuous rotation of the operating member 59'. Mounted upon the end of the shaft 14 is a gear wheel 54 which meshes with a pinion 55 of similar construction to the pinion 41. This pinion meshes with two mutilated gears 56 and 57 similar in construction to gears 42 and 43, so that a complete revolution of these two gears will advance the pinion 55 and gear 54 through a partial revolution. The gear wheels 56 and 57 are loosely mounted upon a sleeve 58, which is mounted upon an operating shaft 40, which is adapted to be rotated by a crank 59'. The shaft 59 is provided with a head 60 at its inner end, to which the sleeve is secured by a set screw 61 carried by a collar 62. Mounted within a recess provided between the sleeve 58 and the shaft 59 is a spring 63, which has its ends 63' bent up, as shown in Figure 10, to project through an opening in the sleeve 58 and to engage the walls of a sector shaped slot 64 provided in the gears 56 and 57. The shaft 14 carries adjacent to the counter-wheel 2 a ratchet wheel 65, which is clearly shown in Fig. 5 of the drawing. This ratchet wheel is engaged by a roller 66 carried upon an arm 67 pivoted to a bar 67' and is spring-pressed inwardly by a spring 68. The operation of this part of the transmitter is as follows: In the normal position of the transmitter, that is, while the shaft 59 is not being rotated, the ends 63' of the spring 63 engage the walls of the opening in the sleeve 58 so that there is no tendency for the gears 56 and 57 to rotate. When, however, the shaft 59 is rotated one wall of the opening in the sleeve 58 will engage one of the ends 63'

of the spring while the other wall of the opening will move away from the other end of the spring so that this last named end now presses against the wall of the slot 64 in the pinions 56 and 57. The further rotation of the shaft 59 will therefore place the spring 63 under tension but the pinions 56 and 57 will not move until the tension of this spring 63 is sufficient to overcome the tension of the spring 68 which holds the roller 66 in frictional engagement with the ratchet wheel 65. When this occurs the gears 56 and 57 will be suddenly partially rotated to cause, through the pinion 55 and the gear 54, a sudden partial rotation of the shaft 14, the roller 66 riding over one of the teeth of the ratchet wheel 65 and then engaging the next tooth of the wheel 65 to prevent further rotation of the counter-wheel until the crank 59' has been further rotated. This feature of the invention is of importance because it permits the operating shaft 59 to be operated in a continuous manner and yet the shaft 14 which is connected thereto will be operated intermittently with a quick acting step by step movement.

The transmitter may, if desired, be provided with a device for obscuring the numbers appearing before the opening in the plate 16 when the range is below 5,000 or above 25,000 yards. This device consists of a shutter 70 with an elongated opening 71 therein which is secured at one end to a disk 72 and at the other end to a hub 73, which hub is shown most clearly in Fig. 5 of the drawing. The disk 72 meshes with a pinion 74, which is loosely mounted upon the shaft 40 (which pinion is of similar construction to the pinion 41) and also meshes with mutilated gears 75 and 76, so that after a complete rotation of the counter-wheel 1 the disk 72 will be partially rotated to throw the upper or lower part of the shutter 70 in front of the opening in the plate 16 to obscure the numbers upon the counter-wheel.

The hub 73, which is secured to the other end of the shutter 70 is engaged by a roller 77 which, when the shutter is not before the opening, rests in a slot 78 in the hub 73, but upon a rotation of the shutter rides upon the curved surfaces 79 or 80. The roller 77 is mounted between arms 81 which are connected to the arms 67 by a spring 68. The upper end of the arm 81 carries a contact 82 which, in the normal position, that is, when the roller 77 is resting in the recess 78, engages a fixed contact 83 carried by the bus bar 32. When, however, the roller rides upon either of the surfaces 79 or 80 this contact is moved to throw the contact 82 out of engagement with the contact 83 to break the signal or lamp circuit closed through these contacts, which circuit will be herein-

after referred to in the description of the electrical connections and the operation of the system.

In Fig. 6 a modified construction of switch is shown. Here the two fixed contacts which are designated 85 and 86 are arranged adjacent each other and the circuit through these contacts is closed by a movable contact 87 which is mounted upon a bell crank 88. The bell crank 88 is pivoted upon a second bell crank 89, as at 90. The bell crank 89 is pivoted to a suitable casing not shown, as at 91, and carries at its upper end a roller 92 which is adapted to engage the cam shaft 36. Also pivoted at 90 are two centralizing arms 96 and 97, which are connected at their upper ends by a spring 98, which spring draws the arms together so that their inner edges engage with a pin 99 carried by the bell crank 88 to hold the pin 99 normally in alignment with the pivots 90 and 91. When the bell crank 89 is actuated by the cam 36 the contact arm 87' will first have an upward or downward movement, depending upon the direction in which the bell crank 89 is moved, which will bring the contact 87 into engagement with one of the fixed contacts 85 or 86. Further movement of the bell crank will then cause the contact 87 carried by the arm 87' to slide on the contact with which it is in engagement, since the bell crank 88 is loosely mounted upon the bell crank 89. The pin 99 will, during such movement, move one of the centralizing arms 96 and 97 out of its normal position, exerting a tension on the parts to return them to normal position after the cam shaft has again been moved with respect to the bell crank 89. The sliding of the contact 87 over one of the fixed contacts 85 or 86 in this manner, will keep these contacts clean so that good contact is at all times assured.

In Figure 2 of the drawing, two receivers are shown in the receiving instrument, which are provided with dials 5 and 6. These receivers are independent of each other and are of the same construction, which construction is clearly shown in Figs. 12 and 13 of the drawing. The receiver comprises two circular end plates 100 and 101, which are joined together by a plurality of iron cores 102, the iron cores being fastened to the end plates by means of screws 103.

Mounted upon each of the cores 102 are two magnetizing coils which have been designated 104 and 105. An annular plate 106 is interposed between the coils and fits against a curved face 102' on each of the cores 102, which rigidly hold the plate in position. Passing through the central opening in the annular plate 106 is an armature shaft 107, which is mounted at its ends in suitable ball bearings in the end plates 100 and 101. The armature shaft 107 carries at its ends armatures 108 and 109, which have

segment-shaped tops 110, from which projects a lateral segmental-shaped flange 111 of less width than the segment-shaped top. The cores 102 are enlarged at their ends to provide poles pieces 112 and 113, which pole pieces have curved inner faces so that the gap between the pole pieces and the armatures is relatively small. The annular plate 106 is provided with a hub 115, which supports two magnetizing coils 116 and 117, which coils serve to polarize the armatures 108 and 109. The coils 116 and 117 are stationary and the armatures freely revolve with the shaft 107 so that the dial 5 which is mounted on the shaft 107 may be turned to different angular positions. To damp the oscillatory movement of the shaft 107, which would be caused by the successive energization and deenergization of the pole pieces, as described, a damping plate or fan 120 is secured to the end of the shaft 107, which fan is enclosed by a suitable chamber 121 which may be filled with any suitable liquid.

In the specific embodiment of the invention shown, five poles and pole pieces are provided and the armatures 108 and 109 are adapted to be held in three intermediate positions between each pair of poles. The different positions are shown by Figs. 13, 14, 15 and 16 and the polarity of the poles and armatures are designated by the letters N and S. The poles are of like polarity and the armatures always remain of unlike polarity, as will be later described.

In Figure 13 three poles are energized, that is, one N and two S. When this occurs, the flanged portion 111 of the S armature occupies a middle position directly beneath the N pole and the N armature is equally attracted by the two S poles.

In Figure 14, which is the first intermediate step from the one shown in Figure 13, only two of the poles are energized, that is, one N and one S, in which instance the armatures move counter-clockwise until the righthand end of the flange 111 of the S armature is coincident with the righthand edge of the north pole and the righthand edge of the N armature is coincident with the right-hand edge of the S pole.

The next step is shown by Figure 15, when two N poles and one S pole are energized, in which instance the flanged portion 111 of the N armature has its ends lying on the radii from the center of the two N poles and the N armature is directly opposite the S pole.

The fourth step is shown in Figure 16, where again two poles are energized, one being N and another S, in which instance the lefthand edge of the flange 111 of the S armature coincides with the left hand edge of the N pole and the lefthand edge of the N armature coincides with the lefthand edge of the S pole.

The next step would bring the pole pieces 130

so that the flange 111 of the S armature would again be medially disposed with respect to the pole piece marked N, in Figure 16.

5 It will therefore be seen that the armatures, and hence the shaft carried thereby, may assume four angular positions in passing from one pole piece to another, and where five poles or pole pieces are utilized, 10 as in the present construction, this permits the rotary shaft to assume twenty independent positions, which correspond to the twenty positions of the transmitter, as will be clear from the description of the connections, in 15 which the various circuit connections are described for energizing the pole pieces.

In the diagram shown in Figure 17, the main supply wires of the system are designated 1^a and 1^b, and the two coils 116, 117 and 116^a, 117^a, which magnetize the armatures 108 and 109 of the two receivers, are shown as connected in parallel across the supply wires, so that as long as the device is in use these armatures are permanently polarized. The coils 104 and 105 of three of the cores 102 have been designated 30^a, 31^a and 32^a, for convenience in describing the operation of the system. The bars which carry the movable switches of the transmitter are designated 17, 18, 19, 20, 21, 22, 23, 24, 25 and 26, corresponding to the reference characters utilized for these bars, as shown in Fig. 3 of the drawings. Each bar is connected to one coil of the receiver, the bars 35 17 to 21 inclusive, being connected to the coils of one receiver actuating dial 6 by wires 3^a, 4^a, 5^a, 6^a, 7^a, and the bars 22 to 26 are connected to the other receiver actuating the dial 5 by wires 8^a, 9^a, 10^a, 11^a, 12^a. As 40 has been described, each pole has two coils or windings which are wound in opposite directions so that the pole pieces at the ends of the core are of the same polarity. The windings of each pole are connected together, as 45 at 13^a and 14^a. Leading from the supply main 1^a and 1^b are wires 15^a and 16^a, which wires lead to the bus bars which carry the fixed contacts 35, the plus wires being connected to the fixed contacts at one side of 50 the transmitter by a wire 17^a and to the minus side by a wire 18^a. A signal lamp 20^a within the receiver casing is also connected across the plus and minus supply wires by a wire 21^a leading from wire 17^a connected to 55 the plus side of the line, which wire 21^a leads to the contacts 82 and 83, which are controlled by the shutter which obscures the numbers upon the counterwheels from view, as has been described. The fixed contact 83 60 is connected from a wire 22^a to a push button 23^a which leads by a wire 24^a to the signal lamp. The other side of the signal lamp is connected to the minus side of the line by a wire 25^a. By closing the push button 23^a 65 the signal lamp within the receiving instru-

ment may be lighted when the receivers are actuated to call to the attention of the person at the receiving stations that the reading has been changed. When, however, the shutter 70 is moved to a position in which its parts obscure the numbers on the counterwheels 1 and 2, the limit contacts 82 and 83 are opened as described, which will prevent any signal from being given in the receiver by the person operating the transmitter. 75 When the transmitter is actuated the circuits through the receiver are therefore as follows. Assuming that the movable switches are closed, as shown in the diagrammatic view from the main supply wire 1^a over the 80 wires 15^a and 17^a to the bus bar 30 through the closed contact which, in this instance, is connected to the transverse bar 24 and wire 10^a through the two windings 30^a of one pole of the receiver, then through the windings 85 31^a of the other pole of the receiver and wire 8^a to bar 32, through the closed contact connected to the bar 32 back to the negative side of the line through wires 18^a and 16^a.

A parallel circuit will also be closed 90 through the windings 32^a connected to the wire 12^a, to the transverse bar 26, to the negative bus bar 32 back to the negative side of the line, so that three poles are energized, and since the windings of each pair are in 95 opposite directions the poles which are energized will be similar to the poles energized in Fig. 13, that is, one north pole and two south poles.

The circuit through the poles of the other 100 receiver will be closed in the same manner, the circuit through the windings connected to the bars 19, 17 and 21 being closed so that the poles of this receiver will also be energized, as shown in Figure 13 of the drawing, 105 so that the armatures of each indicator will assume the position shown in Figure 13. As the transmitter is actuated, the cams which operate the movable contacts of the switches, as described, will successively close the circuits so that the poles of the two receivers will be successively energized, as shown in Figs. 14, 15 and 16, and in this way the armature shaft will be intermittently rotated 110 to successively give the proper readings upon 115 the receiver.

As previously described, the two windings surrounding each core of the receiver which have been designated 30^a, 31^a, 32^a, are wound in different directions so that the 120 pole pieces at the end of each core are of like polarity. The windings 116 and 117 which energize the armature of each receiver are wound in the same direction and are connected in series so that the segment-shaped 125 ends of the armature are always of unlike polarity. The advantage of this construction is that it insures that the armature will always change its angular position when the 130 circuits through the poles of the receiver are

varied. This is true because each segment-shaped end of the armature will be acted on by both an attractive and repulsive force. This will be clear from Figure 13 where the 5 S pole of the armature will be attracted by the N pole at the top of the receiver and repelled by the two S poles at the bottom of the receiver and in the same manner the N pole of the armature will be attracted by the 10 two S poles at the bottom of the receiver and repelled by the N pole at the top of the receiver.

It will be seen from the construction described that where the transmitter and receiver are utilized in connection with a range finder, the rotation of the crank 59', in accordance with the variation in the range, will cause a reading to appear in the transmitter for each change of fifty yards, 15 which reading through the cam shaft and switches described will be transmitted to the receiver, which will have a corresponding reading. It will also be seen that the continuous rotation of the crank 59' will cause 20 the cam shaft 36 connected thereto to be actuated in a step by step manner, the changes in position of the cam shaft occurring suddenly and completely due to the lost motion connection and the ratchet 25 wheel 65 and detent arm 67 which carry the roller 66 engaging the teeth of the ratchet wheel. The cam shaft 37 which is geared to the cam shaft 36 will therefore be moved one complete step each time the shaft 36 30 makes a complete revolution. This will preclude an erroneous reading of the receiver, since the contacts are controlled by the cam shafts and the circuits which are opened and closed to actuate the receivers are actuated practically simultaneously. As before referred to, the receivers are independent of each other and are controlled entirely by the circuits and therefore if the two cam shafts 36 and 37 did not move synchronously, 35 the circuits to one receiver would be controlled prior to the circuits of the other receiver. This would occur when the counter-wheel 2 is moving from its "95" to its "00" indication, for if the counter-wheel 1 which 40 carries the thousands and ten thousands indication and its cam shaft did not then move in synchronism with the counter-wheel 2 and its cam shaft, for example, if the counter-wheel 1 and its cam shaft lagged behind, the receiver actuating the dial 6 would be actuated first and the receiver actuating the dial 5 would remain unactuated. The 45 thousands and ten thousands indication read from the dial 5 would not then give the proper indication, since its reading must be read in connection with the reading of the dial 6. In the construction described, 50 this is avoided, since when the cam shafts of both transmitter switches move they 55 move quickly together a complete step.

It is to be understood that one specific embodiment of the invention has been described herein, and the various novel features of the invention are not limited to the specific structure described, but only by the scope of the claims appended hereto. 70

I claim:

1. In a signal system, a transmitter comprising a plurality of switches, a rotary cam shaft for actuating said switches, and a 75 counter-wheel mounted on said cam shaft.

2. In a signal system, a transmitter comprising a plurality of switches, a rotary cam shaft for actuating said switches, a counter-wheel mounted on said shaft, and 80 means including a lost motion connection for rotating said shaft.

3. In a signal system, a transmitter comprising a rotary cam shaft, a plurality of switches actuated by said cam shaft, a 85 counter wheel mounted on said shaft, said cam shaft being arranged to close one or more of said switches in each different position thereof.

4. In a signal system, a transmitter comprising a cam shaft, a counter wheel mounted on said shaft, a plurality of pairs of switches actuated by said cam shaft, and means for 90 rotating said shaft.

5. In a signal system, a transmitter comprising a rotary cam shaft, a counter wheel carried on said cam shaft, a plurality of switches actuated by said cam shaft each comprising a fixed contact and a pivoted contact actuated to engage said cam shaft. 95

6. In a signal system, a transmitter comprising a rotary cam shaft, a switch actuated by said cam shaft, comprising a fixed contact and a bell crank actuated by said cam shaft, and a pivoted contact carried by said bell 105 crank.

7. In a signal system, a plurality of switches, a plurality of cam shafts for actuating said switches, a counter wheel on each of said shafts, said counter wheels being arranged adjacent each other, and means for 110 rotating said shafts.

8. In a signal system, a plurality of switches, a plurality of cam shafts for actuating said switches, intermittent gearing 115 connecting said shafts, counter-wheels mounted on said shafts, said counter-wheels being arranged adjacent each other, resilient means acting on one of said shafts to cause its quick actuation, and means for rotating one 120 of said shafts including a lost motion connection.

9. In a signal system, a transmitter comprising a driving member adapted to be continuously rotated, a plurality of switches, a 125 cam shaft adapted to be intermittently operated for actuating said switches, gearing connecting said driving member to said cam shaft including a part positively driven from said driving member, a loosely mounted part 130

resiliently connected to said positively driven part, and means for causing said cam shaft to move step by step.

10. In a signal system, a transmitter comprising a driving member adapted to be continuously rotated, a plurality of switches, a cam shaft adapted to be intermittently operated for actuating said switches, gearing connecting said driving member to said cam shaft including a part positively driven from said driving member, a loosely mounted part resiliently connected to said positively driven part, a ratchet wheel carried by said cam shaft, and a resiliently mounted member 10 operating with said ratchet wheel to cause said cam shaft to move step by step.

11. In a signal system, a pair of independent juxtaposed electric step by step receivers carrying indicia which, when combined, give 20 a single reading, a rotary transmitter switch for each receiver, circuits connecting each switch to its respective receiver, a driving member for said switches adapted to be continuously rotated, a transfer mechanism connecting said switches, and means for causing both switches to move together a complete 25 step when the transfer mechanism is actuated.

12. In a signal system, a pair of independent juxtaposed electric step by step receivers carrying indicia which, when combined, give 30 a single reading, a rotary transmitter switch for each receiver, circuits connecting each switch to its respective receiver, a driving member for said switch adapted to be continuously 35 actuated, a transfer mechanism be-

tween said switches, and means for moving said switches step by step for a continuous rotation of said driving member.

13. In a single system, a pair of independent juxtaposed electric step by step receivers carrying indicia which, when combined, give 40 a single reading, a rotary transmitter switch for each receiver, circuits connecting each switch to its respective receiver, a driving member for said switches adapted to be continuously rotated, a transfer mechanism, a lost motion connection interposed between said driving member and said switches, an 45 energy-storing device associated with said lost motion connection and a step by step device 50 associated with said switches.

14. In a signal system, a pair of independent juxtaposed electric step by step receivers carrying indicia which, when combined, give 55 a single reading, a rotary transmitter switch for each receiver, circuits connecting each switch to its respective receivers, a driving member for said switches adapted to be continuously rotated, a transfer mechanism between 60 the switches, a lost motion connection between the driving member and the switches, and an energy-storing member connected to the parts of said lost motion connection and associated with said switches normally holding 65 them stationary but permitting them to be moved step by step by said energy-storing member.

In witness whereof, I subscribe my signature.

HANNIBAL C. FORD.
